LIGHTER

Jean Gaston Tricot, 63 Rue du Val d'Osne, Saint Maurice,
Val de Marne, France

Filed July 15, 1974, Ser. No. 488,765

Claims priority, application France Jan. 15, 1974

Term of patent 14 years

Int. Cl. D27—05

U.S. Cl. D27—42

FIG. 1

FIG. 2

FIG. 3

FIG. 4

FIG. 5

FIG. 6

FIG. 7

FIG. 1 is a top perspective view of a lighter showing my new design;

FIG. 2 is a side elevational view thereof;

FIG. 3 is a view similar to FIG. 2 but from the opposite side of the lighter;

FIG. 4 is the top plan view thereof;

FIG. 5 is a bottom plan view thereof;

FIG. 6 is an elevational view from the left of FIG. 2; and

FIG. 7 is an elevational view from the right of FIG. 2.

I claim:

The ornamental design for a lighter, as shown.
